UNITED STATES PATENT OFFICE.

PAUL H. LANGE, OF BRIDGEPORT, CONNECTICUT, ASSIGNOR TO THE MAX AMS MACHINE COMPANY, OF BRIDGEPORT, CONNECTICUT, A CORPORATION OF NEW YORK.

SEAMING MACHINE.

Application filed October 14, 1926. Serial No. 141,492.

The present invention relates to seaming machines and is an improvement on the construction shown in Letters Patent No. 941,755 of November 30, 1909.

5 The main object and feature of the invention is to produce a construction that is more flexible, more readily and extensively adjustable to compensate for inaccuracies of various kinds, and withal more rugged, substantial 10 and simple in character.

In the accompanying drawings the invention is disclosed in a concrete and preferred form in which

15 Fig. 1 is a vertical sectional view of a seamer head, with parts broken away and omitted, embodying the invention.

Fig. 2 is a horizontal sectional view substantially on the plane of line 2—2 of Fig. 1.

20 Fig. 3 is a horizontal sectional view substantially on the plane of line 3—3 of Fig. 1.

Fig. 4 is a detail view in elevation of some 25 of the parts shown in Fig. 1.

Fig. 5 is a view partly in elevation and partly in section looking in the direction of arrow 5 of Fig. 1.

Fig. 6 is a horizontal sectional view substantially on the plane of line 6—6 of Fig. 5.

Fig. 7 is a vertical sectional view of the 30 rotatable support for the seaming tools.

Fig. 8 is a bottom plan view looking in the direction of arrow 8 of Fig. 7.

1 is a stationary shaft carrying at its lower end a chuck 2 that cooperates with a pedestal, not shown, to clamp the body and cover in 35 manner well understood.

3 is a rotatable seaming tool support loosely mounted on shaft 1. The seaming tool support is composed of a sleeve portion 4 and a carrying member 5 in the form of a disc having two opposed radial slots 6. Suitable means are provided for rotating the support, in the present instance taking the form of a gear 7, carried by the sleeve, to which motion is imparted by another gear, not shown, 40 in a manner well known. The top of gear 7 is provided with guides 8 which carry slideable boxes 9 for the support of pivots 10 of bearings 11 that carry shafts 12. These latter have bearings 13 slidably mounted in slots 50 6 of the carrying member. Shafts 12 have gears 14 at their upper ends in constant mesh with stationary gear 15, and also have gears 16 at their lower ends that move in and out of mesh with gear 17 at the lower end of shaft

1. Seaming tools 18 are also carried at the 55 lower ends of shafts 12. It will now be understood that rotation of member 3 causes the seaming tools to travel in an orbit around the work clamped between the chuck and pedestal and also causes each seaming tool to rotate 60 on its own axis.

Suitable means are provided to tilt shafts 12 on centers 10 to bring the seaming tools into and out of engagement with the work; and, in the present case, these means take the 65 following form: 19 is a worm carried by shaft 1 and with this worm engage two worm gears 20 that extend in through openings 21 in sleeve 4. 22 and 23 indicate two cam shafts,

70 mounted on the supporting member, each of which carries a worm gear 20 by which it is driven. These two shafts are parallel and are arranged on opposite sides of the machine and at each end of each cam shaft is a cam, 75 indicated respectively by 24 and 25, the former of which is fast to its cam shaft and the latter of which is loose thereon. Said cam

shafts also carry each two gears 26 and 27, the former of which is fast to its shaft and the latter of which is loose thereon; and the 80 arrangement is such that each gear and its adjacent cam moves in unison and also that gear 26 of one shaft meshes with gear 27 of the other shaft so that each worm drives two cams, one on each shaft: or, to put it differ-

85 ently, the cams at one end of shafts 22 and 23 are driven in unison or together and the cams at the other end of shafts 22 and 23 are driven in unison or together. The object of this construction is that the cams at one end of shafts 90

22 and 23 are used to tilt one shaft 12 while the cams at the other end are employed to tilt the other shaft 12. From the foregoing it 95 will be understood that rotation of the supporting member causes rotation of the cam shafts and of the cams.

Mounted on the supporting member as by means of brackets 28 are two pivots 29 and 30, each pivot carrying two levers 31 and 32 and each lever having a cam roll 33. These cam 100 rolls engage the cams on the cam shafts. The lower ends of levers 31 are connected to the slideable boxes 13 of one of shafts 12 and the lower end of levers 32 are connected to the slideable boxes 13 of the other shaft 12 by the 105 following means. 34 is a pin carried at the lower end of each lever and loosely connected to the pin is a rod 35 that passes through an

extension 36 of bearing 13. The arrangement is in duplicate on each side so that the connections virtually constitute a yoke, and it will be perceived that when levers 31 or 32 are rocked boxes 13 will be caused to slide. Nuts are associated with rod 35, which latter is threaded, so that proper adjustments can be made. Pin 34 also carries a projection 37 that acts against a spring 38 surrounding rod 39 and abutting against abutment member 40 so that when box 13 moves toward the work said spring 38 is compressed, the spring acting to restore the parts when rotation of the cams permits this action to take place. Abutment 40 and rod 39 are carried by member 5. In the case of the first operation roller or seaming tool, the projection indicated by 36 is rigid with box 13 but, in the case of the second operation roller, the projection consists of a bar 41 tiltably held by screw and nuts 42 and springs 43 are employed so that when the second operation roller passes over the extra thickness of material, produced by the side seam of the body, said roller and box 13 may recede and this receding action will be taken up by said springs 43 without causing movement of levers 32. In addition to the foregoing, a positive stop may be employed to limit the inward movement of the boxes 13, and such stop is in this case afforded by a member 44 pivotally connected to box 13 and passing through a bar 45; nuts 46 limiting the inward movement.

By the foregoing means it is possible to compensate for unavoidable variation, due to shrinkage in hardening, in the size of the seaming rollers; for minor variations in thickness of tin plate; for extra metal thickness at the side seam; for expansion of chucks and rollers on account of heating developed while the machine is in operation; and to prevent the seaming roller from coming in contact with the chuck when running idle.

I claim:

1. The combination with a tilttable seaming tool shaft pivotally supported at one end and slidingly supported at the other, of pivotally supported levers, cams to actuate said levers, connections extending from said levers to the slidably mounted end of the shaft, and spring means to normally urge the levers and thereby the slidable end of the shaft in one direction, and spring means admitting of movement of the slidable end of the shaft in the same direction independently of the movement of the levers.

2. The combination with a tilttable seaming tool shaft pivotally supported at one end and slidingly supported at the other, of pivotally supported levers, cams to actuate said levers, connections extending from said levers to the slidably mounted end of the shaft, spring means to normally urge the levers and

thereby the slidable end of the shaft in one direction, spring means admitting of movement of the slidable end of the shaft in the same direction independently of the movement of the levers, and means to positively limit the movement of the slidable end of the shaft in a direction opposite to that in which the springs urge it.

3. The combination with a tilttable seaming tool shaft pivotally supported at one end and slidingly supported at the other, of pivotally supported levers, cams to actuate said levers, lateral extensions associated with the slidable end of said shaft, connections from said levers to said extensions, spring means to normally urge the levers and thereby the slidable end of the shaft in one direction, and spring means admitting of movement of the slidable end of the shaft in the same direction independently of the movement of the levers.

4. The combination with a tilttable seaming tool shaft pivotally supported at one end and slidingly supported at the other, of pivotally supported levers, cams to actuate said levers, lateral extensions associated with the slidable end of said shaft, connections from said levers to said extensions, spring means to normally urge the levers and thereby the slidable end of the shaft in one direction, spring means admitting of movement of the slidable end of the shaft in the same direction independently of the movement of the levers, and means to positively limit the movement of the slidable end of the shaft in a direction opposite to that in which the springs urge it.

5. The combination with two cam shafts, of tilttable seaming tool shafts, and means to tilt the latter by rotation of the former including: a cam at each end of each cam shaft, one loose and the other fast on said shafts, means for rotating the cams at the same ends of the two cam shafts in unison, and connections from said cams to said seaming tool shafts.

6. The combination with a carrying member, of two oppositely disposed tilttable seaming tool shafts pivotally supported at one end and slidingly supported at the other on said carrying member, pivotally supported levers, cams to actuate said levers, connections extending from said levers to the slidably mounted ends of the shafts, oppositely disposed abutments on the carrier, and spring means interposed between the levers and the abutments tending to move the shafts away from each other.

Signed at Bridgeport, in the county of Fairfield and State of Connecticut this 11th day of October, 1926.

PAUL H. LANGE.
